(57) **CLAIM**

The ornamental design for gel curing lamp, as shown and described.

DESCRIPTION

FIG. 1 is a front perspective view of the gel curing lamp showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a bottom view thereof with the base plate retracted. The broken lines in FIGS. 1-4 and 6-9 of the drawings are for the purpose of illustrating portions of the gel curing lamp, which form no part of the claimed design.

1 Claim, 5 Drawing Sheets
